(57) **CLAIM**

The ornamental design for a guitar amplifier with digital audio disc player, as shown and described.

DESCRIPTION

FIG. 1 is a front view of a guitar amplifier with digital audio disc player showing our new design;

FIG. 2 is a rear view thereof;

FIG. 3 is a top plan view thereof;

FIG. 4 is a bottom view thereof;

FIG. 5 is a left side view thereof, a right view being symmetrical to the left side view;

FIG. 6 is a sectional view thereof taken along line 6—6 in FIG. 1; and,

FIG. 7 is a reduced perspective view thereof.
